UNITED STATES PATENT OFFICE.

LAURENCE S. LACHMAN, OF NEW YORK, N. Y.

KNOCKDOWN STRUCTURE.

1,203,207.

Specification of Letters Patent. Patented Oct. 31, 1916.

Application filed December 6, 1910. Serial No. 595,956.

To all whom it may concern:

Be it known that I, LAURENCE S. LACHMAN, a citizen of the United States, and a resident of the city, county, and State of New York, have invented certain new and useful Improvements in Knockdown Structures, of which the following is a specification.

This invention relates to structures such as columns, poles, towers, masts, beams, girders, concrete reinforcements, etc., and has for its main purpose the provision of a structure of the kind stated which may be stored or transported in knockdown condition, readily and easily assembled for use, and when assembled will be strong and durable.

Other objects and advantages of the invention will appear from the hereinafter description of the preferred embodiments thereof.

In the accompanying drawings, wherein like characters of reference designate like parts in the several views: Figure 1 is a vertical sectional view of a part of a structure embodying the present improvements, showing the several members assembled in their proper relative positions. Fig. 2 is a detail representation exemplifying a specifically different means for securing the parts together than those shown in Fig. 1. Fig. 3 is a detail representation exemplifying a specifically different means for securing the parts together, than those of the preceding figures.

The structure of the present invention essentially includes a plurality of longitudinal members, a plurality of connecting members therefor, and keepers for securing said members together and maintaining the connecting members in a predetermined position upon the longitudinal members. In practice, the longitudinal members are relatively disposed in positions which act in cord with the shape of the structure which is to be produced, and at distances apart determined by the requirements of such structures, and the connecting members are arranged along the length of the longitudinal members maintained against displacement longitudinally of the latter by the keepers, which are of such character as to form seats therefor. The shape of the structure in cross section may be round, angular or otherwise, as desired; the connecting members extend around the same

in engagement with either the outer or inner surfaces of the longitudinal members; and the keepers may be integral with the longitudinal members, or formed separate therefrom, as desired, and may be of various characters, all as exemplified by the herein illustrated embodiments of the invention. These are general features of the invention, particularly important ones being that the parts be of such correlative nature that they will form a structure of the kind herein set forth which may be stored or shipped in knock-down condition and in compact space, and may be quickly and readily assembled, (at the place of use, if so desired) and when assembled may be quickly and rigidly secured together without welding, riveting or other like means of fastening.

Various desirable embodiments of the invention are exemplified in the drawings, and it is apparent that these will suggest others which are contemplated to be within the spirit of the invention and the scope of the subjoined claims.

Referring now to the drawings and particularly describing the forms of the invention exemplified by each of the same: The structure illustrated in Figs. 1 and 2 is of skeleton nature and substantially circular in cross section. It is composed of a series of longitudinal strips, marked 50, spaced apart and connected with each other at various places along their lengths by rings, marked 51 and 53, which also are spaced apart. The keepers or seats marked 52 are shown as formed by crimps or depressions in the longitudinal members 50. These receive the connecting members 51 and 53. This figure exemplifies the use of round rods for the longitudinal members. Stretchers or spacers marked 58 may be removed when the parts are assembled or may be permitted to remain as a permanent part of the structure.

In Fig. 2, a further exemplification of keepers integral with the longitudinal members is indicated. In this figure a longitudinal member, marked 40, is shown as having its edge formed with an aperture, 42, adapted to receive the portion of the connecting member, marked 41, which intersects said member, and to provide a lip or flange, marked 43, which, as shown in dotted outline in said figure, is bent over the connecting member to hold the latter in its seat.

In Fig. 3 there is shown a keeper, 72,

which is of hook form and is secured to the longitudinal member, marked 70, by entering its stem into an aperture in the latter. This keeper secures the connecting member, 5 marked 71, by having its hook end extending over the latter. In practice, this keeper, preferably, is primarily a rod or bar secured to the longitudinal member by having its end suitably fastened in a recess of the latter, and is given this hook form after the parts have been assembled, its outer end being bent over the connecting member to secure the latter; but, if desired, it may be primarily of hook form and be driven to 10 place in the longitudinal member to secure the connecting member after the latter has been arranged in position on said longitudinal member.

It is believed that the manner of assembling the parts and the advantages of the invention will be apparent from the foregoing, but attention is called to the fact that the longitudinal members may be kept in stock, or stored, with the keepers thereon 20 and may be shipped in the quantity and of the length desired, with the connecting members, to the place of installation, where the structure may be quickly erected, it being only necessary there to assemble the 25 members in their proper relative locations and secure them together by bending the ends of the keepers over the connecting members. This association of the parts and bending of the keepers obviously may be 30 quickly and inexpensively done by labor possessing no special skill. It will be noted that relative predetermined positions of the connecting members are indicated by the keepers and that said keepers will serve to 35 support the connecting members while the parts are being assembled.

The reference herein to the structure as a knockdown one is founded upon the ease with which the parts may be put together, 40 more particularly than to imply that it may

be readily taken apart but it is apparent that it may be taken apart much more readily than would be possible if the parts were integrally united or riveted together.

It will of course be understood that the 50 invention is not restricted to the particular forms herein exemplified, and that many other forms, structures and arrangement of parts contemplated to be within the spirit of the invention and the scope of the subjoined claims will readily suggest themselves. 55

Having now described the invention what I believe to be new and desire to secure by Letters Patent, is: 60

1. A knockdown structure for reinforcing concrete comprising oppositely disposed longitudinal members having groups of seats arranged respectively on opposite sides thereof and separable endless connecting 65 members, each connecting member engaging a group of said seats.

2. A knockdown structure for reinforcing concrete comprising oppositely disposed longitudinal members having groups of depressions arranged respectively on opposite sides thereof to form seats, separable curved connecting members arranged parallel to each other engaging a group of said seats. 70

3. A knockdown structure for reinforcing 75 concrete comprising oppositely disposed longitudinal members having groups of depressions arranged respectively on opposite sides thereof adapted to form seats, separable rings engaging said seats on the outside and 80 on the inside respectively of the longitudinal members.

In witness whereof I have hereunto set my hand at the city, county and State of New York, this 25th day of November, 1910. 85

LAURENCE S. LACHMAN.
